UNITED STATES PATENT OFFICE.

CHARLES WILBUR MEGUIAR, OF SONORA, KENTUCKY.

APPARATUS FOR DISPENSING DENTAL MATERIALS.

1,386,193.

Specification of Letters Patent.

Patented Aug. 2, 1921.

Application filed February 8, 1917. Serial No. 147,511.

To all whom it may concern:

Be it known that I, CHARLES WILBUR MEGUIAR, a citizen of the United States, residing at Sonora, in the county of Hardin 5 and State of Kentucky, have invented certain new and useful Improvements in Apparatus for Dispensing Dental Materials, of which the following is a specification, reference being had therein to the accompanying 10 drawing.

This invention relates to a dispensing apparatus, which while not limited to such use, is adapted more particularly for the use of dentists in the mixing of mercury and 15 alloys to form amalgams.

Considerable difficulty has heretofore been experienced by dentists in gaging the proper proportions of mercury and alloy to obtain the desirable and proper results, the 20 more usual or common practice being to pour from bottles or the like, a certain quantity of mercury and alloy, the relative proportions of which being largely guess work on the part of the operator. Both dental al- 25 loys and mercury are very difficult materials to handle and control, and frequently im- proper mixtures are obtained with unsatisfactory results. Again if too much of one material or the other is discharged from the 30 containers, it is quite difficult as well as unsanitary to replace the same in the containers. In an effort to obtain a proper mixture of the materials, intricate and delicate scales or balances have at times been 35 resorted to, but in view of the expense, time consumed, and the required necessary skill in the manipulation and use of the scales, the same have not been generally adopted or gone into extensive use.

Attempts have been made to provide a satisfactory substitute for scales whereby proper mixtures of the alloys and mercury may be obtained, but in no single instance with which I am familiar have the means or 45 devices gone into use or proven practical or given satisfactory results, largely owing to inaccuracy in operation and other objections, more particularly due to the partic- 50 ular character of the material operated upon, the susceptibility of the alloys to cling to the surfaces and compact at the point of discharge, etc., which would prevent the de-

livery of defined predetermined and uniform quantities of the material.

It is the object of the present invention to 55 provide a novel, efficient, and thoroughly practical dispensing apparatus, which will overcome the various objections heretofore recognized, and to make possible a true and accurate "balance" of the materials, and 60 at the same time so protect the materials in the mixing and measuring operations that they will be substantially free from dust, dirt, or other impurities or contaminations.

In carrying out the invention, it is pro- 65 posed to provide in operative association a container for the mercury, and a receptacle or receptacles for one or more alloys with novel means for discharging predetermined 70 quantities of the material at will, such means in the preferred embodiment of the invention being of a character whereby the discharge from the container and receptacle may be simultaneously controlled.

It is a further object of the invention to 75 provide in operative association, the containers for the mercury and alloy, and means for supporting the same in position, whereby any accidental discharge of the material is largely avoided, and in order to 80 move thoroughly protect the parts from outside influence or accidental operation, it is also preferred to provide a suitable in- 85 closing casing permitting of ready access to the operating parts as desired.

It is a further object of the invention to provide a container for mercury or the like, and a receptacle for alloy or the like, the one constituting a support or carrying medium for the other and all of the parts being ar- 90 ranged in a novel and compact form.

A further object of the invention is to provide in operative association with the mercury and alloy containers a common dis- 95 charge member, and a suitable mixing tube to receive the materials to the end that so soon as discharged, the materials will be delivered to the mixing tube or receptacle without intermediate hand manipulation or the like or exposing the materials to outside 100 influence.

It is a further object of the invention to provide novel and improved means for accurately determining the relative propor-

tions of mercury and alloy to be discharged, and means whereby this relative proportion of the materials may be accurately varied.

Another feature of the invention resides 5 in means whereby in adjusting the relative proportions of the materials to be discharged, the operator will be guided by an indicator of novel and improved type.

Another feature of the invention resides 10 in means whereby the container for the alloys will be supported whereby to prevent accidental discharge of the alloys, and means whereby measured quantities of the alloys may be delivered at will, together 15 with means for preventing compacting of the alloys at the point of discharge, which might interfere with an accurate and uniform discharge.

A further feature of the invention resides 20 in the provision of a movable receptacle for alloys or the like and novel means for actuating the receptacle to discharge predetermined amounts of the alloy at will.

The invention further includes means for 25 accurately determining the amount of mercury to be delivered, and means whereby this amount may be varied or adjusted at will.

Again, the invention includes a novel type 30 of container for the mercury and the like, and novel means for normally closing said container and permitting a refilling of the same at will.

More particularly, the invention includes 35 a container for mercury or the like and one or more alloy receptacle carriers mounted upon said container and plunger actuating means for discharging from the container and receptacles the mercury and alloy either together or separately.

40 Many other improvements and novel details in the construction and arrangement of the parts of the invention will be understood from the description to follow, which for a clear understanding of the invention is 45 to be considered in connection with the accompanying drawings which form a part hereof, and wherein is disclosed, for the purpose of illustration, convenient and satisfactory embodiments of the invention.

50 In the drawings:—

Figure 1 is a front elevation of the apparatus with the casing, supporting means, and discharging member removed.

Fig. 2 is a transverse section substantially 55 on the line 2—2 of Fig. 1.

Fig. 3 is a section view, the inclosing casing being removed.

Fig. 4 is a vertical section of the actuating means for one of the movable receptacles, 60 said section being taken substantially on the line 4—4 of Fig. 2.

Fig. 5 is a side elevation of the apparatus, parts being shown in section, and broken away.

65 Fig. 6 is a vertical section of the appa-

ratus, parts being broken away, said section being taken substantially on the line 6—6 of Fig. 1.

Fig. 7 is an enlarged detail view of a slightly modified construction of mixing 70 tube, the inner and outer surfaces of the wall 63 tapering.

With more particular reference to the drawings, wherein like reference numerals refer to corresponding parts throughout the 75 several views, 1 is a suitable supporting base conveniently having a rearward extension 1^a with a downwardly offset supporting

flange 1^b adapted to be detachably secured in place as by screws or bolts 2 engaging 80 a support 3 broken away and conveniently of a character adapted to be applied to a wall or the like. In this connection, it is

understood of course that the supporting 85 flange 1^b may be directly secured to the wall or the like. Positioned upon the base 1, conveniently centrally of the latter and detachably secured thereto as by bolts or

screws 3^a is a container for mercury or the 90 like comprising a front wall 4, side walls 5, rear wall 6 and a bottom wall 7, the said walls surrounding a cylindrical chamber for the mercury, and the front wall having one or more transparent portions, two being shown at 7^a whereby to constitute sight 95 openings, that the condition of the contents may at all times be observed from a point without the container. The bottom wall 7 of the container has a suitable downwardly

extending central projection 8 positioned 100 within a central aperture 9 of the base 1 and projecting slightly therebelow, the said projection 8 surrounding a discharge opening 10 through the bottom of the container. The opening 10 connects with an enlarged 105 annular recess 10^a in the bottom wall. The outer surface of the lower end of the projection 8 is conveniently tapered at 8^a, whereby to form a knife edge at its lower terminal, to facilitate the discharge of the 110 mercury and avoid clinging tendency of the latter. It is quite important that accurate discharges of the mercury in uniformly measured quantities be provided for and to this end a novel construction of valve mech-

anism and actuating means therefor is provided which conveniently takes the form of a closure valve or stopper 11 of substantially the diameter of the opening 10, whereby to effectively close the same while permitting of longitudinal slidable movement of the closure 11 in said opening. The closure valve is provided with an annular recess or groove 12 adapted in the upward movement of the valve to receive a supply 125 of mercury, dependent upon the size of the groove and in the lowering movement of the valve to carry the mercury downwardly to a point beyond the knife edge 8^a that the same may be discharged, and to assist the 130

ready discharge from the valve, the lower end of the latter has preferably a cone-shaped recess 13 whereby to provide a knife edge 13^a. While the valve as thus far described will be found to be quite useful in the discharge of measured quantities of the mercury, at the same time, it is found quite convenient and desirable to provide means whereby the amount of mercury to be discharged may be varied at will, since the relative proportions of mercury and alloy are different according to the desired uses, or according to the particular character of alloy employed. With this in view, one wall of the annular groove 12 is preferably provided by an offset shoulder 14 connecting the head of the valve with a suitable stem 15 whereas the opposite wall of said groove is preferably provided by the lower edge 16 of a sleeve 17 surrounding said stem, the said walls 14 and 16 being relatively adjustable in a manner to be now described.

The sleeve 17 projects above the top of the container and is provided with a threaded portion of reduced diameter 18 adapted to be engaged by an interiorly threaded portion 19 of a surrounding sleeve 20, which latter connects with a head or finger engaging disk 21. The stem 15 of the valve has a shouldered portion 22 connecting with an upwardly projecting rod or stem part 23 terminating at a point above the upper end of the sleeve 17 and within a central recess of the surrounding sleeve 20. Said surrounding sleeve 20 has a threaded recess 24 adapted to receive a screw pin 25, the pin of which latter is adapted to engage a suitable recess in the rod or stem extension 23, whereby said rod or stem 23 will have imparted thereto a rotatable or lengthwise movement according as to whether the operating disk 21 is rotated or moved lengthwise. Any suitable means may be employed to prevent rotatable movement of the sleeve 17 during the rotation of the stem 23 in the lengthwise adjustment of the valve 11, the said means in the illustrated embodiment herein taking the form of a guide pin 26 adapted to engage a vertically extending guide groove 27 in the inner surface of the rear wall 6 of the container. It will be observed that as the operator grasps the engaging disk 21 and imparts rotation thereto, the valve 11 will be adjusted vertically in one direction or the other because of the threaded engagement of the sleeve 20 with the sleeve 17 which latter as just described is fixed from rotation. Any lengthwise adjustment of the valve 11 will in turn vary the depth of the groove 12. In order to avoid accidental rotation of the disk 21 and connected parts, a suitable spring 28 is conveniently mounted upon the rod or stem 23 adapted to engage an abutment formed by a reduced portion of the sleeve 17 and the

shoulder 22 formed by the stem part 15 of the valve. The said spring 28 tends to maintain the valve from accidental rotation by frictional engagement as will be obvious. The top wall 29 of the container is preferably adjustable and removable at will, the same having a hollow depending annular flange 30 having a threaded periphery to engage the internal threads on the wall of the container. The said flange 30 is provided with one or more openings 31, which in one position of the top 29 will be closed by the surrounding wall of the container and which in the vertical upward adjustment of the top 29 will be exposed above the top of the body of the container, whereby mercury or the like may be fed into the chamber of the container through said openings 31, as by a funnel or an ordinary medicine dropper. The upper surface of the adjustable top 29 is provided with an annular recess 32 adapted to receive the lower end of a suitable helical spring 33, the upper end of which is fixed in an apertured portion of the sleeve 17 as at 34. The tendency of the spring is to exert upward pressure on the same connected to the actuating disk 21 and associated parts, the upward movement under the action of the spring being limited by an abutment 35 adapted to engage the undersurface of the adjustable top 29. It will be appreciated in this connection that should the top 29 be adjusted vertically by reason of its threaded connection, a sufficient distance, the valve 11 under the action of the spring 33 will likewise be elevated to an extent whereby to be positioned above the bottom wall 7 of the container with the result that an unrestricted outlet for the mercury would be provided, and in order to obviate this possibility, a suitable set screw or the like is provided to limit the upward adjustable movement of the top 29 in the filling of the container through the opening 31. This set screw is indicated at 36, the same having an adjustable threaded engagement at 36^a with the top wall of the body of the container and the head of the screw being adapted to overlie the upper surface of the adjustable top 29, and when properly adjusted will permit of the upward movement of the said top 29 a sufficient distance to allow for filling through the openings 31 but not a sufficient distance to position the lower end of the valve 11 above the outlet opening in the bottom of the container.

Operatively associated with the mercury container are one or more auxiliary containers or receptacles for alloy, two being shown for the purpose of illustration and a description of one will suffice for both, it being understood that these receptacles are preferably arranged one upon each side of the mercury container. While various types of receptacles may be employed in connec-

tion with the supporting frame to be now described, it is desirable and preferable to employ a receptacle 40 of the character illustrated in Fig. 1 of the drawings, the same taking the form of a cylindrical tubular transparent body part having a conical closed upper end and an apertured lower end, the aperture having a surrounding tube projecting upwardly within the body portion, to a point adjacent the terminal of the conical end, whereby to provide a restricted inlet at this point and whereby in the movement of the receptacle, to deliver measured quantities of the alloy through said tube. The inlet end of the tube being slightly spaced from the conical closed end of the receptacle, it will be noted that in one movement of the receptacle the material will find its way into the space between the inlet end of the tube and the conical end of the receptacle, and in the opposite movement of the receptacle the said material will be discharged through the tube from the receptacle. This receptacle constitutes the subject-matter of a divisional application filed concurrently herewith. 41 is a carrying frame conveniently tubular and having at one or more edges, spring fingers 42 adapted to yieldably engage the peripheral wall of the container and frictionally hold the same in place. In this connection however, it is sometimes desirable to positively secure the container in position, and with this in view, a retaining screw 43 is provided. This screw is threaded through the frame 41 and has a pointed inner terminal which, assuming that the receptacle is formed of gelatin or other penetrable material will penetrate the wall of the container to not only secure the same firmly in place but to prevent subsequent reuse of the container by an unscrupulous person who might seek to refill the same with an inferior product. A gear wheel 44 is fixed upon a projection 41^a of the annular frame 41, said projection having a collar 45 at a point to the inner side of said gear wheel, the side walls 5 of the mercury container are provided with annular recesses for the reception of the collar 45 and gear 44 of each frame for the alloy receptacles as well as a vertically extending slot 46 adapted for the reception of slidable plungers 47 and 48 respectively one for each of the frames 41. Each of the plungers 47 and 48 is provided with a rack portion 49 adapted to engage the teeth of the gear 45 to impart rotatable movement to said gear. The downward movement of the plungers is limited by the lower end of the rack contacting with the base plate 1, whereas the upward movement is limited by the upper end of the rack portion of the plunger engaging an abutment 50 formed by the wall surrounding the slot 46. The upper ends of the plungers 47-48 are provided with de-

tachable extensions 47^a and 48^a respectively having preferably screw threaded engagement with the body portion of the plungers as illustrated at 51 and terminating at the upper end in finger engaging disks or heads 47^b and 48^b respectively. Suitable spiral springs 52 are interposed between the top of the mercury container and a shouldered portion 52^a provided by the lower end of the detachable extension members 47^a-48^a, said springs being sleeved upon each of the plungers 47-48, whereby to normally exert upward pressure on the plungers. It will be observed that in the normal position of the receptacles 40, the cone-shaped closed end will be positioned uppermost in the frames 41, the arrangement of the rack and gear being such that when the plungers 47 and 48 are in elevated position under the action of the springs 52, the tubular frames 41 are in substantial vertical alignment with the side walls 5 of the mercury container.

Should it be desired at any time to remove either the plungers 47-48 of the receptacle frames 41, it is only necessary to detach the threaded extensions 47^a-48^a and the springs 52, when the rack end of the plungers may be removed from the lower end of the container. The racks 49 being in overlapped relation with the collars 45 serve to retain the gear wheels in place and so soon as the racks are removed, the gears as well as the frames 41 may be likewise removed. The gear wheels 44 are provided with a gearless or stripped portion 44^a to facilitate the application and removal of the plungers into and through the slotted portions 46 of the container.

The parts are constructed and arranged whereby in the normal position thereof, all of the actuating disks or plunger heads 21, 47^b and 48^b are arranged in substantially the same horizontal plane and immediately adjacent to one another to the end that the various plungers may be actuated by a finger or fingers of the single hand of the operator at will either independently or simultaneously.

The base 1 is preferably provided with an annular groove 60 adapted for the reception of the lower end of a suitable globe or inclosing housing, conveniently of glass as illustrated at 61, Fig. 5, the said globe being open at the top thereof at a point below the plunger heads or disks whereby the same may be readily operated without removal of the globe. When not in use, a removable closure or top 62 of any desired construction is fitted to the top of the globe and together with said globe constitutes a protecting housing to prevent the entrance of dust, etc., to the apparatus.

It is desirable to protect the mixture from outside influences and to deliver the same

directly into what may be termed a mixing chamber 63 conveniently formed of glass and having a normally closed conical lower end 64 with the inner surface of said chamber gradually tapering outwardly from said conical portion toward the upper end thereof. The tubular mixing chamber may take the conical formation illustrated in Fig. 7, if desired. This tubular mixing chamber or 5 receptacle is adapted to be rapidly agitated, preferably through the medium of a mechanism which constitutes the subject-matter of a divisional application filed concurrently herewith by myself and in the embodiment 10 of the invention herein illustrated is adapted to be frictionally engaged and held by a metallic coupling 65 having a yieldable engaging surface or surfaces 66. The upper portion of the coupling member 65 is adapted to be fitted in any desired manner to the lower tubular terminal 67 of a discharge chute or funnel 67^a, conveniently of glass and detachably held in position as by headed screws or bolts 68 projecting from the 15 undersurface of the base 1 and adapted to overlie the outer surface of the funnel or chute at the top thereof. Other securing means may in this connection be provided.

In the art to which the invention more 20 particularly relates, *i. e.* dentistry, it is the practice to utilize different characters of alloys at times, and it may be assumed that two different characters of alloys are contained in the receptacles 40 and that it is de-

25 sired to mix therewith a predetermined quantity of mercury. The relative proportion of mercury and alloy will differ according to the nature of the latter, and the mercury discharging means is preferably ad- 30 justable for this purpose. It is quite essential in this connection that the operator be accurately guided in making the necessary adjustment and with this in view, coöperating 35 guiding means is provided on the plun- 40 gers which guiding means conveniently takes the form of an annular series of indicating divisions 69 on the disk or head of the intermediate plunger 21, and a pointer in the form of a line or groove 70 on one 45 or both of the disks or heads of the plungers 47-48. The plungers 47 and 48 being ar- 50 ranged to discharge predetermined quantities of alloy the relative proportional quantity of the mercury will be determined 55 by rotatable movement of the head or disk 21 to bring the proper division of the series of indicating divisions 69 conveniently ap- 60 propriately designated by numerals, in reg- 65 istration with the indicating slot 70. As 70 has been seen, the rotation of this disk 21 will increase or decrease the size of the mer- 75 ury seat 12 in the plunger valve 11.

In the operation of the device, assuming that a quantity of one or the other of the alloys is desired the operator presses down-

wardly on the operating head of the particular plunger 47 or 48 which through the medium of the rack 49 will rotate the gear wheel 44, whereby to invert the normal position of the receptacle 40 and position the 70 alloy at the conical end of the receptacle and opposite the open end of the discharge tube. Thereupon, the operator releases the plunger which under the action of the spring 52 will return the receptacle 40 to normal 75 position and a measured quantity of the alloy will discharge through the internal tube and into the funnel or chute 67 whence to be delivered into the mixing tube 63. Assuming that it is desired to simultaneously de- 80 liver the mercury with the alloy the operator places the same or another finger on the operating head or disk 21 of the intermediate plunger and simultaneous with the lowering movement of one of the side plungers to control the discharge of the alloy a given quantity of the mercury which has found a seat in the groove 12 will be separated from the body of the mercury and forced downwardly until out of contact with the tubular projection 8, surrounding the central aperture in the base 1, said separated quantity of the mercury falling from out of said seat into the funnel or chute and thence into the mixing tube 63.

90 It is understood of course that the base plate 1 is provided with openings 1^c preferably elongated to allow for the discharge therethrough of the alloys from the recep- 95 tacles 40 in the operation of the latter.

100 It is further understood that the casing which constitutes the mercury container is preferably formed of metal or material of a character to have no effect upon the mercury and of a character to be unaffected by the 105 mercury, and conveniently the other parts associated with the casing are of metallic formation.

110 It has been appreciated that while the plungers 21 controlling the discharge from the mercury container and 47^a-48^b controlling the discharge from the alloy receptacles may be simultaneously operated to control at one operation the discharge of alloy and mercury, at the same time the discharge of 115 mercury from its container is governed by a downward movement of the plunger 21 whereas the discharge from the receptacles 40 is governed by the releasing movement of the plungers 47^a-48^b in the return operation 120 thereof. This operation is of importance, *i. e.* the discharge of the mercury slightly prior to the discharge of the alloy for the reason that when mercury contacts with a surface, it tends to break up and scatter, 125 clinging to the adjacent walls in minute globules. In the present apparatus, the discharge for the alloy operating to permit the alloy to follow the mercury, the alloy acts as a brushing or cleansing instrumentality, 130

thereby forcing any adhering mercury globules from the walls of the container to a common center.

It will also be seen that since the base 7 of the mercury container is provided with a central annular recess 10^a of less diameter than the body portion of the mercury chamber proper and of greater diameter than the plunger opening 10 in the base of the container, there will always be maintained in said recess a sufficient head or weight of mercury surrounding the annular recess 12 to be discharged by the latter even after the mercury falls to a point below the upper surface of the bottom wall of the container.

What I claim is:—

1. A dispensing apparatus for dental use comprising a vertically disposed container for mercury or the like, a vertically disposed receptacle for alloy or the like, the receptacle for alloy being supported from the mercury container and adapted to be rotated from a position in which its discharge end is arranged uppermost to a position in which its discharge end is arranged lowermost whereby to discharge material therefrom, the mercury container having an outlet in the base thereof, a valve to control said outlet, and vertically movable actuating means 30 to move said valve and rotate said receptacle whereby the mercury and amalgam may be simultaneously discharged.

2. A dispensing apparatus for dental use comprising a vertically disposed container for mercury or the like, a vertically disposed receptacle for alloy or the like, the receptacle for alloy being supported from the mercury container and adapted to be rotated from a position in which its discharge end is arranged uppermost to a position in which its discharge end is arranged lowermost whereby to discharge material therefrom, the mercury container having an outlet in the base thereof, a valve to control said outlet, and vertically movable actuating means to move said valve and rotate said receptacle whereby the mercury and amalgam may be simultaneously discharged, and a common discharge member adapted to receive the simultaneous discharge of mercury and amalgam.

3. A dental dispensing apparatus for discharging predetermined quantities of material such as amalgam and mercury, comprising a fixed receptacle for one of such materials, a movable receptacle for the other of such materials, said receptacles being connected one to the other, whereby they constitute in effect a single unit, the first-mentioned receptacle having a measuring valve-controlled outlet, and actuating means adapted to be operated independently or simultaneously, whereby to actuate the valve control to discharge material from one of such receptacles and whereby to bodily move

the coöperating receptacle to bring its outlet into discharging position.

4. In an apparatus for discharging measured quantities of the material for forming dental amalgams and the like, the combination of a stationary container for mercury having a discharge outlet, means for delivering from the container a predetermined supply, a receptacle for alloy mounted for swinging movement upon the first mentioned container and having a measuring discharge outlet to discharge adjacent the first mentioned outlet, and means for moving said receptacle to discharge a measured quantity of the material therefrom, both of said means being adjacent one another whereby the same may be simultaneously operated by the single hand of the operator.

5. In a dispensing apparatus for dentists' use, the combination of a container for one material, a receptacle for the coöperating material connected thereto and relatively movable, said receptacle having a measuring discharge opening, a measuring valve-controlled opening for the container, plunger-actuating means for moving said valve to discharge the one material and for moving said receptacle whereby to position its discharge to emit a predetermined amount of the coöperating material, and means for adjusting said measuring valve whereby the relative proportions of the materials discharged from the container and receptacle may be regulated.

6. In a dispensing apparatus of the character described, the combination of a container for mercury or the like, a receptacle for alloys or the like connected therewith and relatively movable, said receptacle having a measuring discharge opening, means for moving said receptacle to discharge a predetermined amount of material therefrom, a measuring valve controlled opening for the container, a plunger actuating device for said valve, and a plunger actuating device for the receptacle, said plungers being arranged adjacent to one another, for simultaneous operation or independent movement as desired.

7. In a dispensing apparatus of the character described, the combination of a container for mercury or the like, a receptacle for alloys or the like connected therewith and relatively movable, said receptacle having a measuring discharge opening, means for moving said receptacle to discharge a predetermined amount of material therefrom, a measuring valve controlled opening for the container, a plunger actuating device for said valve, a plunger actuating device for the receptacle, said plungers being arranged adjacent to one another for simultaneous operation or independent movement as desired, and means whereby the dis-

charge from the receptacle and the container may be relatively adjusted at will.

8. In a dispensing apparatus of the character described, the combination of a receptacle for alloy or the like having a discharging means adapted to by an oscillating movement of the receptacle discharge a predetermined quantity of its contents, a carrying frame for the receptacle, a container for mercury or the like, and a slideable plunger mounted on the container and operatively connected to the frame to oscillate the same.

9. In a dispensing apparatus of the character described, the combination of a receptacle for alloy or the like having a discharging means adapted to by an oscillating movement of the receptacle discharge a predetermined quantity of its contents, a carrying frame for the receptacle, a container for mercury or the like, and a slideable plunger mounted on the container and operatively connected to the frame to oscillate the same, said plunger being spring held in one position to prevent accidental discharge of the material.

10. In a dispensing apparatus of the character described, the combination of a receptacle for alloy or the like having a discharging means adapted to by an oscillating movement of the receptacle discharge a predetermined quantity of its contents, a carrying frame for the receptacle, a container for mercury or the like mounted on said frame, and a slideable plunger mounted on the container, said plunger having a rack surface and said frame having a connected pinion or gear to be actuated by the rack and thereby oscillate the receptacle.

11. In a dispensing apparatus of the character described, the combination of a receptacle for alloy or the like having a discharging means adapted to by an oscillating movement of the receptacle discharge a predetermined quantity of its contents, a carrying frame for the receptacle, a container for mercury or the like mounted on said frame, and a slideable plunger mounted on the container, said plunger having a rack surface and said frame having a connected pinion or gear to be actuated by the rack and thereby oscillate the receptacle, and spring means for actuating the plunger in one direction, and means for limiting the movement of the plunger in opposite directions.

12. In a dispensing apparatus of the character described, the combination of a container for mercury having a controllable discharge adjacent the lower end thereof, one of the side walls of the container having a recess therein, a gear mounted in said recess, a frame connected to said gear adapted to support a receptacle for alloy or the like having a discharge opening, and a vertically movable plunger slidably mounted

in said wall of the casing and having a rack to engage said gear.

13. In a dispensing apparatus of the character described, the combination of a casing having a chamber for mercury or the like, vertically movable plungers in opposite walls of the casing, each plunger having a rack surface, a pinion to engage the racks, and an oscillating receptacle carrying frame arranged at opposite sides of the casing one for each rack, said oscillating frames being connected with said gear means.

14. In a dispensing apparatus of the character described, the combination of a casing having a chamber for mercury or the like, vertically movable plungers in opposite walls of the casing, each plunger having a rack surface, a pinion to engage the racks, an oscillating receptacle carrying frame arranged at opposite sides of the casing one for each rack, said oscillating frames being connected with said gear means, a discharging chute connected to said casing and adapted to receive the discharge from said casing and the receptacles carried by said frames.

15. In a dispensing apparatus of the character described, the combination of a casing having a chamber for mercury or the like, vertically movable plungers in opposite walls of the casing, each plunger having a rack surface, a pinion to engage the racks, an oscillating receptacle carrying frame arranged at opposite sides of the casing one for each rack, said oscillating frames being connected with said gear means, a discharging chute connected to said casing and adapted to receive the discharge from said casing and the receptacles carried by said frames, and an oscillating vertically movable plunger arranged between the first mentioned plungers on the casing having a measuring valve at the lower end thereof to control the discharge from the container formed by said casing.

16. In a dispensing apparatus of the character described, the combination of a tubular receptacle of transparent penetrable material for alloy or the like, said receptacle having a measuring discharge outlet controllable by an oscillating movement of the receptacle, a movable supporting frame for the receptacle, and holding means on the frame adapted to puncture the receptacle and fixedly retain the same in place.

17. In a dispensing apparatus, the combination of a tubular receptacle for alloy or the like, said receptacle having a closed end and an opposite apertured end, a discharge tube surrounding the aperture and projecting inwardly to a point adjacent the closed end whereby to permit of measured quantities of the material being discharged from the receptacle upon a movement thereof, means for supporting the receptacle and

maintain the same in upright position with the closed end uppermost, and means for positively and accurately moving said support to discharge a measured quantity of the material from the receptacle.

18. In a dispensing apparatus, the combination of a tubular receptacle for alloy or the like, said receptacle having a closed end and an opposite apertured end, a discharge tube surrounding the aperture and projecting inwardly to a point adjacent the closed end whereby to permit of measured quantities of the material being discharged from the receptacle upon a movement thereof, and means for supporting the receptacle and maintain the same in upright position with the closed end uppermost, said supporting means for the receptacle having means to puncture the receptacle to fixedly retain the same in place.

19. In a dispensing apparatus, the combination of a tubular receptacle for alloy or the like, said receptacle having a closed end and an opposite apertured end, a discharge tube surrounding the aperture and projecting inwardly to a point adjacent the closed end whereby to permit of measured quantities of the material being discharged from the receptacle upon a movement thereof. 25 means for supporting the receptacle and maintaining the same in upright position with the closed end uppermost, means for oscillating said supporting means for the receptacle whereby to discharge measured quantities therefrom, said means comprising a movable plunger mounted on a casing, said plunger having a rack, and said supporting means for the receptacle having a gear to engage the rack.

40 20. In a dispensing apparatus, the combination of a tubular receptacle for alloy or the like, said receptacle having a closed end and an opposite apertured end, a discharge tube surrounding the aperture and projecting inwardly to a point adjacent the closed end whereby to permit of measured quantities of the material being discharged from the receptacle upon a movement thereof, means for supporting the receptacle and 45 maintaining the same in upright position with the closed end uppermost, means for oscillating said supporting means for the receptacle whereby to discharge measured quantities therefrom, said means comprising a movable plunger mounted on a casing, said plunger having a rack, said supporting means for the receptacle having a gear to engage the rack, the rack when in position constituting means for retaining the gear and the supporting means for the receptacle 50 in place on the casing, and said rack being removable to permit of detachment of the receptacle frame.

60 21. In a dispensing apparatus of the character described, the combination of connect-

ed containers, one of said containers having an outlet in the bottom wall thereof, a vertically movable plunger having an annular recess, said plunger being movable through the opening in the bottom of the receptacle, and means whereby upon movement of the plunger a measured quantity of the material will position itself in said recess and be ejected by the plunger through the bottom of the receptacle, and means whereby the size of said recess may be adjusted at will.

70 22. In a dispensing apparatus of the character described, the combination of a vertically disposed receptacle for mercury or the like having an opening in the bottom wall thereof, a slideable valve for said opening, a vertically movable top wall for the container, a vertically movable plunger for the valve projecting through the opening in the top wall of the container, said valve having a circumferential groove or recess adapted 75 in the upper position of the plunger to receive a quantity of mercury and in the lowering movement of the plunger to discharge the mercury through the outlet opening in 80 the container, and said top having a depending flange with an inlet aperture therethrough adapted in the upper movement of the top to be exposed above the body of the container.

85 23. In a dispensing apparatus of the character described, the combination of a vertically disposed receptacle for mercury or the like having an opening in the bottom wall thereof, a slideable valve for said opening, a vertically movable top wall for the container, a vertically movable plunger for the valve projecting through the opening in the top wall of the container, said valve having a circumferential groove or recess adapted 90 in the upper position of the plunger to receive a quantity of mercury and in the lowering movement of the plunger to discharge the mercury through the outlet opening in 95 the container, and said top having a depending flange with an inlet aperture therethrough adapted in the upper movement of the top to be exposed above the body of the container, spring means interposed between the top and the plunger whereby to normally hold the same in elevated position, and means for limiting the upward movement of the top whereby when the inlet aperture is exposed the valve for the outlet from the container will remain in closing position.

100 24. In a dispensing apparatus of the character described, the combination of a receptacle for alloy or the like, said receptacle being formed of penetrable material and having a restricted discharge opening, and means for supporting said receptacle in position whereby to prevent discharge of the material through said opening, said means permitting of a movement of the receptacle to discharge the material, and said means 105 110 115 120 125 130

also being adapted to penetrate one wall of the receptacle substantially as and for the purpose described.

25. In an apparatus for dispensing dental materials, the combination of a support, a receptacle mounted for swinging movement on the support, said receptacle having a closed end normally disposed uppermost and an open end with a discharge tube projecting upwardly to a point adjacent the closed end and within the receptacle, spring means for normally holding said receptacle in position with the closed end uppermost, and actuating means for moving the receptacle 10 to a reverse position whereby to permit a given quantity of the material to find its way to the inlet end of the discharge tube.

15

26. In an apparatus for dispensing dental materials, the combination of a support, a receptacle mounted for swinging movement

20

on the support, said receptacle having a closed end normally disposed uppermost and an open end with a discharge tube projecting upwardly to a point adjacent the closed end within the receptacle, spring means for normally holding said receptacle in position with the closed end uppermost, and actuating means for moving the receptacle to a reverse position whereby to permit a given quantity of the material to find its way to the inlet end of the discharge tube, a discharge chute adapted to receive said material as the spring returns the receptacle to normal position, and an auxiliary receptacle on said support adapted to simultaneously discharge to said discharge chute a given quantity of another material.

In testimony whereof I hereunto affix my signature.

CHARLES WILBUR MEGUIAR.
